UNITED STATES PATENT OFFICE.

FERDINAND G. MOARD, OF TURTLE CREEK, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,338,321.

Specification of Letters Patent. Patented Apr. 27, 1920.

Application filed July 3, 1916. Serial No. 107,453.

To all whom it may concern:

Be it known that I, FERDINAND G. MOARD, a citizen of the United States, and a resident of Turtle Creek, in the county of Allegheny and State of Pennsylvania, have invented a new and useful Improvement in Control Apparatus, of which the following is a specification.

My invention is of general application but 10 relates more specifically to control apparatus and particularly to fluid-actuated mechanisms for operating drum controllers.

One object of my invention is to provide 15 a device of the above-indicated character that shall be relatively inexpensive to construct, compact and of light weight.

Another object of my invention is to provide 20 a device in which relatively short cylinders, that may be constructed from pressed steel, may be used.

Heretofore, such fluid-actuated devices as have been proposed for operating controller drums, have embodied relatively long 25 cast-iron cylinders and a plurality of opposing pistons mounted on the same rods and adapted for reciprocal operation within the cylinders. Such relatively long cylinders may be satisfactorily formed by casting only and, because of inherent flaws in the cast- 30 ings, a large proportion of the cylinders leak and must either be sealed with an impregnating compound or discarded.

My invention provides the use of stationary piston stems and two short cylinders 35 that are secured in an end-to-end alinement and have reciprocal operation with respect to the coöperating stationary piston stems. The relatively short cup-shaped cylinders used in the device hereinafter described may 40 be formed from pressed steel, thereby effecting a material saving in the expense of the cylinder member and providing a cylinder member of relatively light weight and great strength.

Figure 1 of the accompanying drawing is 45 a top view, partially in section and partially in plan, of a control device embodying my invention; Fig. 2 is a sectional view on the line II—II of Fig. 1; Fig. 3 is a sectional view on the line III—III of Fig. 1, and Fig. 50 4 is a schematic diagram of the proposed control apparatus embodying a modified operative connection between the actuating cylinders and the control drum.

The device shown in the drawing com-

prises a base 1, a plurality of piston stems 2 that are rigidly attached to the base member, a plurality of cup-shaped cylinders 3 that are secured in end-to-end alinement and are disposed around the piston stems 2, 60 magnet valves 4 and 5 for controlling the admission of fluid, under pressure, to the cylinders 3, and a rotatably mounted drum 6 that is operatively connected to the cylinders 3 by a saddle 7.

The base member 1 has a plurality of like supports 10 mounted thereon, to each of which the corresponding piston stems 2 are respectively secured. One of the magnet valves 4 and 5 is secured to each of the supports 10. A fluid-inlet duct 12 extends from each of the fluid-supply pipes 13 through the supports 10 to the corresponding magnet valves 4 and 5 and a duct 14 provides a passageway from each of the magnet valves 75 through the corresponding piston stem 2 to a cylinder 3. A sealing gasket 15 provides a fluid-tight joint between the support 10 and the fluid inlet pipe 13. The magnet valves 4 and 5 are, respectively, an inverted valve 80 and a standard valve of usual construction. The inverted valve 4, which is schematically illustrated in Fig. 4, is adapted to admit fluid from the pipe 13 to the cylinder 3 through the opening 9 when the valve is de- 85 energized and to establish a passageway from the cylinder 3 through the opening 11 to the atmosphere when the valve is energized. The standard valve 5 is adapted to establish a connection from the cylinder 3 to 90 the atmosphere when the valve is deenergized and to admit fluid to the cylinder 3 when the valve is energized. The hollow piston stem 2 has a piston head 17 secured thereto by a hollow bolt 18 which is provided with a head and is adapted to be threaded into the hollow valve stem 2. The piston head 17 comprises a base washer 19, a preferably leather gasket 20, an expander 95 21, a follow washer 22 and a lock washer 23. 100 The hollow bolt 18 provides for the admission of fluid from the duct 14 to the cylinder 3. The cup-shaped cylinders 3 are secured to an interposed disk 24, in end-to-end relation, by a rivet 8 that makes a fluid-tight joint with the cylinders 3. The disk 24 has two oppositely and outwardly-projecting lugs 25 that are adapted to coöperate with the saddle 7 to actuate the drum member 6.

The drum 6 is rigidly attached to a shaft 26 110

which is rotatably mounted on the uprights 27 and is secured to the saddle 7. A plurality of contact fingers 28 are adapted to engage suitable conducting segments that are mounted upon the drum 6.

A proposed modification of the connecting means between the cylinders 3 and the drum 6 is illustrated in Fig. 4 and is adapted to rotate the cylinders 6 through a greater angle than would be possible by the use of the saddle 7. A rack 29 is rigidly attached to the side of the cylinders 3 and is adapted to engage a pinion 30 that is secured to the shaft 26. This modification avoids the use of the interposed disk 24 and thereby economizes space and weight.

To operate such a device as I have herein described, the magnet valves 4 and 5 are energized to admit fluid, under pressure, to the right-hand cylinder 3 from the valve 5 and establish a connection from the left-hand cylinder to the atmosphere through the valve 4, thereby actuating the cylinders to the left. If it is desired to stop the motion of the cylinders at any point, the valve 4 is deenergized which immediately establishes an opposing pressure in the left hand cylinder and thereby stops further movement of the device.

30 Although I have described my invention

in a simple and preferred form, it is capable of various modifications, and I desire that only such limitations shall be imposed as are indicated in the appended claims.

I claim as my invention:

1. In a piston device, a piston stem, a piston head and a hollow bolt securing said head to said stem, said head comprising a base washer, a gasket, an expander, a follow washer and a lock washer. 35

2. As an article of manufacture, a pair of cup-shaped pressed-steel cylinders rigidly secured in end-to-end relation by a rivet making a fluid-tight connection therewith. 40

3. The combination with a plurality of 45 alined piston members, of a pair of cup-shaped cylinders operatively disposed around said pistons and a disk interposed between said cylinders and secured thereto.

4. The combination with a plurality of 50 alined piston members, of a pair of cup-shaped cylinders operatively disposed around said pistons and a disk having a plurality of outwardly-extending arms interposed between said cylinders and secured 55 thereto.

In testimony whereof I have hereunto subscribed my name this 27th day of June, 1916.

FERDINAND G. MOARD.
